UNITED STATES PATENT OFFICE.

HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC HEATER.

1,143,579.

Specification of Letters Patent. Patented June 15, 1915.

Application filed October 31, 1911. Serial No. 657,813.

To all whom it may concern:

Be it known that I, HARRY W. DENHARD, a citizen of the United States, residing at San Francisco, in the county of San Francisco and State of California, have invented new and useful Improvements in Electric Heaters, of which the following is a full, clear, concise, and exact description, reference being had to the accompanying drawing, forming a part of this specification.

This invention relates to electric heaters.

One of the objects of the invention is to provide an improved electric heater.

Another object is to provide an improved heater in which a plurality of heating coils, adapted for different heating purposes, are automatically controlled by an object to be heated.

A further object is to provide an improved curling iron and grease paint heater.

Other objects and advantages of the invention will hereinafter appear.

The accompanying drawings illustrate an embodiment of the invention.

25 In the views of these drawings: Figure 1 shows a central section view through a heater. Fig. 2 shows a sectional view on line 2—2 of Fig. 1. Fig. 3 shows an end view of the heater. Fig. 4 shows a diagram 30 of the circuit connections for the same.

For purposes of illustration, I have shown a curling-iron heater arranged beneath a grease paint heater between end members of a suitable frame. A switch mechanism controlling the circuit connections of the same is located on a plate beneath the curling-iron heater and between the end members. In the construction shown the end members and the bottom plate are carried on the side of 35 a base or panel, as shown in Fig. 3, so that this panel may be readily attached to any suitable surface, or, if desired, the device may be portable and set against any surface without attaching the same.

40 The base 1 is preferably formed of a suitable insulating material and carries a bottom plate 2 clamped to it and extending from it at right angles. This bottom plate 2 is preferably formed of insulating material 45 and provided with end members 3, preferably formed of cast metal, which in turn may be attached to the base 1. In a preferred form the curling-iron heater is constructed substantially in the same manner 50 as my co-pending application, Serial No. 55

657,811, filed Oct. 31, 1911, including a metal sleeve 4 set in the end members 3 and inclosed in a sheet of insulation 5; a resistance material 6, of any desired type, being wound upon the sheet of insulation and inclosed in 60 a sealed heat-retaining chamber 7. As in the previous construction, the door 8 is arranged to close the openings in one of the end members opposite the open end of the sleeve 4, and this door is provided with an 65 extension 9 arranged to transmit the movement of the door to the switch mechanism.

The grease paint heater is preferably arranged above the curling-iron heater and includes a heating element preferably of a flat 70 type, wherein a resistance material 10 is preferably inclosed between two or more sheets of insulation 11, as illustrated in Fig. 1. The heating unit is preferably located within the ends of the end members and the 75 grease pan 12 having inwardly extending grease-holding chambers 13 is preferably snugly fitted upon the ends of the frame and attached to the same by means of suitable screws or other devices 14. By the arrangement of the grease paint heater directly beneath the grease pan 12, I am able to provide a heater wherein the heat is directly conducted to this pan. Further, by the arrangement of the grease pan upon the top of 80 the device it is very conveniently located, and is heated not only by the heat developed by its unit but also that developed by the heating unit for the curling-iron.

85 The switch mechanism, which is operated upon movement of the door 8, is connected with the extension 9 on the door so that it is operated when the door is either opened or closed. In a preferred form, links 15 are attached to the lower end of the extension 9 and are so arranged that when the door is moved about its pivot 16 a movable contact member 17 on a shaft 18 is thrown about its axis to change the circuit connections at 90 contacts 19, 20, 21 and 22 carried upon the bottom plate 2. In a preferred form, an upwardly extending projection 23 is struck up from the contact member 17 and engaged by the hooked end of one of the links 15. The contact members 19, 20, 21 and 22 are 95 preferably fixed to the top surface of the bottom plate 2 by means of suitable bolts 24 and are preferably provided with downwardly extending portions 25 which are 100 preferably forced into the material of the 105

base to hold the contact members securely in position. The shaft or spindle 18, which carries the movable contact member 17 extends through a suitable opening 26 in the 5 bottom plate and an opening of smaller diameter in a metal plate 27 carried on the upper surface of said bottom plate and attached to the same by means of screws or other suitable devices 28. The upper end of 10 the shaft 18 is squared as shown in Fig. 2 so that the contact 17 moves with it. In a preferred form, a spiral spring 29 encircles the lower end of the spindle 18, having one end fixed in a suitable opening in the plate 15 27 and the other end fixed in a suitable tap or sleeve 30 carried by the spindle. It will thus be seen that when a curling iron or other object is inserted in the heater the door is opened and the switch is actuated 20 against the bias of spring 29. When the object is removed the door and the switch are automatically and quickly returned to their normal position by the spring.

In Fig. 4 I have illustrated diagrammatically one form of circuit connections which may be used with my improved heater. As shown in this figure the heating coil 10 of the grease paint heater is arranged in parallel with the heating coil 6 of the 25 curling-iron heater. In a preferred form, the heating coil for the curling-iron heater is so arranged that it consumes a greater amount of energy than the heating coil for the grease paint heater. The normal position of the switch mechanism is shown in 30 Fig. 4 with the movable contact member 17 bridging the contacts 20, 22. In this position the grease paint heater is in circuit and the curling-iron heater is cut out of circuit. 35 When the curling-iron or other object to be heated is inserted in the heating chamber within the coil 6, the door 8 is opened, throwing the movable contact 17 to break the circuit at the contacts 20, 22 and to make the 40 circuit across the contacts 19 and 21. The curling-iron heater is then in circuit and the grease paint heater is cut out. Due to the 45 fact that the curling-iron heater consumes a larger amount of energy than the grease paint heater, sufficient heat will be obtained 50 for the operation of both heaters when the curling-iron heater is in use, without the necessity of connecting the grease paint heater in circuit. Thus a very convenient 55 arrangement is provided whereby a person desiring to use the grease paint heater alone may do so at any time, by throwing a suitable line switch 31 of any desired construction. When, however, it is desired to use the 60 curling iron heater and at the same time use the grease paint heater, the circuit for the curling-iron is automatically closed upon insertion of the curling-iron without the necessity of operating any distinct switch, and at 65 the same time, the grease paint contained in

the pans is kept at the proper temperature without reducing the amount of energy being supplied to the curling iron heater. When the curling iron has been sufficiently heated, it is withdrawn from the heater and the circuit of the curling iron heater is immediately broken automatically, the spring return for the switch mechanism tending to keep the door closed and on its return cutting in the grease paint heater. Of course, 70 if the grease paint has reached the proper temperature and it is only desired to use the same for a short time thereafter, the line switch 31 may be opened; the residual heat in the device being sufficient to maintain the 80 grease paint at the proper temperature for a short time.

In a preferred form a projection or ledge 85 32 is provided upon the forward edge of the heater casing which may serve as a receptacle for the curling iron when it is not in use. Further, if desired, the grease pans 10 may be removable, so that they will snap into position upon the top of the frame. It is obvious that other forms of base member than that herein shown may be provided and that the base may, if desired, be arranged beneath the bottom plate 2 so that the device may be entirely portable and stand upon the 95 base.

By my improved construction I have provided an improved heater which may be made up into a very compact form so that it occupies but little space upon a dressing-table. Further, the arrangement is such that the grease paint heater is not in the way of the person using the curling iron heater. By my improved method of control, the heating device may be cut out of circuit when desired, or the curling iron heater or 100 grease paint heater may be in circuit at different times. Further, while when the larger amount of energy required for the curling iron heater is needed, the grease paint heater is cut out, by my improved arrangement the grease paint is still kept at the proper temperature and consistency. My improved heater is so constructed and arranged that the parts of the same are effectually insulated from each other so that 105 there is no danger of short-circuiting or overheating, and the device is very safe in operation. The device may further be made up in such a form that it may readily be placed in a trunk and carried with the user. If desired, the terminals for the device may be connected to an ordinary socket plug so that all that it is necessary to do is to place the plug in circuit when it is desired to use the heater. By the use of the spring pressed 110 switch I am able to provide a switch which breaks the circuit quickly and with a minimum of sparking, and at the same time, through its connection with the door, acts to 115 provide an automatic means of closing the 120 switch. The door is provided with a 125

door and conserving the heat within the device. Further, by my improved construction I have provided a heating device which is very rugged and well adapted to withstand long usage, which may be made up into very light form so that it may be readily carried about. Further, the device is of such a simple construction that it may be readily manufactured at small expense.

10 While I have in this application specifically described one form which my invention may assume in practice, I do not wish to be limited to this specific form, chosen for purposes of illustration, but wish to cover 15 within the scope of this application all of those forms of my invention falling within its spirit.

What I claim as new and desire to secure by Letters Patent is as follows:—

20 1. In an electric heating device, a plurality of heating coils adapted to heat a plurality of objects and means actuated by the placement of an object to be heated within the heating zone for changing the current 25 flow in said coils.

2. In an electric heating device, a frame having a heating chamber formed therein, a door for said chamber, a plurality of heating coils adjacent said chamber adapted to 30 heat a plurality of objects, and means actuated upon movement of said door for changing the circuit connections of said coils.

3. In an electric heating device, a frame having a heating chamber formed therein, a heating coil for said chamber, a second heating coil carried in said frame, a door for said heating chamber, and means actuated upon movement of said door for cutting in the said first mentioned coil and cutting out 40 the said second mentioned heating coil.

4. In an electric heating device, a casing having a heating chamber formed therein, a heating coil for said chamber, a second heating coil carried by said casing, and means actuated by the insertion of an object to be heated in said heating chamber for cutting in the heating coil for said chamber and cutting out the other heating coil.

5. In an electric heating device, a casing 50 having a heating chamber formed therein, a heating coil surrounding said chamber, means for supporting an object to be heated upon said casing, a heating coil heated beneath said means and means actuated upon the insertion of an object to be heated in said chamber for supplying current to the heating coil for said chamber and changing the circuit connections of the other coil.

6. In an electric heating device, a frame, 60 a sleeve forming a heating chamber carried in said frame, a heating coil for said chamber, a pan carried by said frame, a heating coil for said pan and means actuated upon the insertion of an object to be heated in said sleeve for cutting in the heating coil

for the same and changing the circuit connections of the other heating coil.

7. In an electric heating device, a frame, a sleeve carried thereby, a heating coil wound about said sleeve and insulated therefrom, a pan carried by said frame above said coil, a heating coil for said pan between said pan and said first mentioned coil and means actuated upon the insertion of an object to be heated in said sleeve for supplying the current to its coil and cutting off the current supplied to the heating coil for said pan.

8. In an electric heating device, a frame, a hollow heating unit supported therein, 75 means for supporting an object to be heated carried by said frame, a second heating unit located between said means and said hollow heating unit and means actuated upon insertion of an article to be heated in said hollow unit for supplying the current to said unit and decreasing the heat supplied to said object.

9. In an electric heating device, a frame, a sleeve carried thereby, a cylindrical heating coil surrounding said sleeve and insulated therefrom, a pan carried by said frame above said coil, a second coil between said pan and said coil and means actuated upon an insertion of an object to be heated in said sleeve for changing the circuit connections of said coils.

10. In an electric heating device, a frame, a heating unit inclosed in a sealed chamber therein, a second heating unit carried 100 by said frame and means actuated by an object to be heated by one of said units for changing the circuit connections of said units.

11. In an electric heating device, a frame, 105 a heating unit inclosed in a sealed chamber therein, an object to be heated carried by said frame, a second heating unit adjacent said object and means actuated by another object to be heated by one of said units for 110 changing the circuit connections of said units.

12. In an electric heating device, a frame, a heating unit carried thereby and inclosed in a sealed chamber, a second unit mounted 115 in said frame, each of said units being arranged to heat different objects and a switch mechanism actuated by a movement of an object to be heated by one of said units for changing the circuit connections of one of 120 said units.

13. In an electric heating device, a frame, a sleeve carried thereby, a heating coil surrounding said sleeve and inclosed in a sealed chamber, a second heating unit mounted in 125 said frame adjacent said chamber, a support for an object to be heated mounted adjacent said last mentioned unit and means including a spring pressed contact member arranged to change the circuit connections of 130

said heating unit upon the movement of an object to be heated by one of said units.

14. In an electric heating device, a casing having a ledge formed thereon, a transversely extending plate connecting the end members of said casing, a hollow heating unit carried between the end members of said casing and inclosed in a sealed chamber, a flat heating unit carried in said casing above said first mentioned unit, a pan mounted on said casing adjacent said flat unit, a door normally closing one of the ends of said hollow heating unit, and a switch mechanism actuated upon movement of said door and mounted upon said bottom plate for changing the circuit connections of said unit.

15. In an electric heating device, a frame, a heating coil supported therein, a heating pan carried by said frame, a heating coil for said pan, and an oscillating spring-pressed contact member carried by said frame and actuated upon movement of an object to be heated to move in a plane parallel to the axis of the heating coil in the frame to change the circuit connections of said coils.

16. In an electric heating device, a frame having an opening therein, a plurality of heating coils adjacent said opening, means for closing said opening operable upon movement of an object to be heated, an oscillating spring-pressed contact member carried by said frame and movable in a plane parallel with the plane of said heating coils, and means connecting said contact member and said closing means serving to operate said contact member upon movement of said closing means.

17. In an electric heating device, a panel, a frame mounted thereon, a heating unit extending longitudinally of said frame and having an opening adapted to receive an

object to be heated, a heating unit carried by said frame adjacent said first mentioned unit, a pan carried by said frame adjacent said unit, and means operated upon insertion or removal of an object to be heated by said first mentioned coil for changing the circuit connections of said coils.

18. In an electric heating device, a frame having end members, a heating unit carried between said end members and communicating with an opening in one of the same, a second heating unit carried by said frame, a heating pan carried by said frame adjacent said second unit, means operable upon movement of an object to be heated by said first unit for changing the circuit connections of said units, and means carried by said frame adapted to support said object to be heated by said first mentioned unit when the latter is not in use.

19. In an electric heating device, a panel, a frame carried thereon and having end members spaced apart, an insulating base connecting the bottoms of said end members, a cylindrical heating unit carried between said end members and communicating with an opening in one of the same, a second heating unit carried between said end members above said first mentioned unit, a grease pan carried by said end members adjacent said second mentioned unit, and means carried on said insulating base and operable upon movement of an object to be heated by said first mentioned unit for changing the circuit connections of said units.

In witness whereof, I have hereunto subscribed my name in the presence of two witnesses.

HARRY W. DENHARD.
